UNITED STATES PATENT OFFICE.

THOMAS McCORMICK AND ANANIAS MILLER, OF MOUNT PLEASANT, PENNSYLVANIA, ASSIGNORS OF ONE-FIFTH TO GEORGE A. SCHAEFER, ONE-FIFTH TO JOSIAH F. MILLER, ONE-TENTH TO HENRY H. SCHAEFER, AND ONE-TENTH TO WALTER J. KEIST, OF ALLEGHENY, PENNSYLVANIA.

CARBURETER.

No. 856,654.

Specification of Letters Patent.

Patented June 11, 1907.

Application filed June 29, 1905, Serial No. 267,674.

To all whom it may concern:

Be it known that we, THOMAS McCORMICK and ANANIAS MILLER, citizens of the United States, residing at Mount Pleasant, in the county of Westmoreland and State of Pennsylvania, have invented a new and useful Carbureter, of which the following is a specification.

This invention relates to improvements in means for supplying charges of motive fluid to explosion engines.

One of the principal objects is to provide a novel and exceedingly simple structure, wherein the hydrocarbon or other fluid employed will be thoroughly vaporized, only as rapidly as required by the engine, and is delivered to the engine or explosion chamber thereof in proper condition to be exploded, the apparatus operating with a high degree of efficiency and economy.

A further and important object is to provide a carbureter from which a plurality of engines can be supplied with motive fluid, each engine being operable without regard to the condition or relation of any other connected to the carbureter.

The preferred embodiment of the invention is illustrated in the accompanying drawings, wherein:

Figure 1 is a vertical longitudinal sectional view through the new carbureter. Fig. 2 is a horizontal sectional view on the line 2—2 of Fig. 1. Fig. 3 is a cross-sectional view on the line 3—3 of Fig. 1. Fig. 4 is a top plan view of the upper perforate partition.

Similar reference numerals designate corresponding parts in all the figures of the drawings.

In the embodiment illustrated, a casing is employed comprising a bottom 5, side walls 6, end walls 7, and a top 8. Interior upright walls 9 divide the casing into outer mixing chambers 10, and an intermediate vaporizing chamber, the latter of which has a detachable cover 11, comprising a section of the top 8, that bears upon the upper edges of the walls 9, and is packed by a suitable gasket 12, the cover being fastened in place by any suitable means, as, for instance, bolts 13.

The carbureting chamber has extending across its upper and lower portions, partitions 14 and 15, spaced apart, the upper par-

tition 14 being spaced from the cover 11 and forming therewith an air compartment 16. The lower partition 15 is spaced from the bottom 5, forming a vapor compartment 17, which compartment is in communication with the mixing chambers 10, by means of perforations 18, formed in the interior walls 9, below the partition 15. A perforated tube 19, preferably rectangular in cross section, as illustrated in Figs. 2 and 4, has an open lower end in communication with the vapor compartment 17, the perforations communicating with the space between the partitions 14 and 15. The interior of the tube is cut off from communication with the air chamber 16, preferably by extending the upper end of said tube to the cover 11 of the vaporizing chamber. A body of absorbent hydrocarbon-holding material 20, is interposed between the partitions 14 and 15 and surrounds the tube 19. This material may be anything suitable for the purpose, such as asbestos, waste, or the like. The upper partition is provided in its upper side with a hydrocarbon-receiving channel 21, extending about the tube 19, said partition having perforations 22, located on opposite sides of the channel. The lower partition 15 is also provided with perforations 23. The cover 11 has a suitable supply opening 24, which may be closed by a plug, as 25.

The air compartment 16 of the vaporizing chamber has through its cover an air inlet 85 opening 26, closed by an inwardly opening check-valve 27, which valve is normally held closed by a spring 28, one end of the spring bearing on a yoke 29, bridging the opening, the other end of the spring bearing against a nut 30, threaded upon the stem of the valve and adjustable to vary the resistance to the opening movement of said valve. The mixing chambers 10 are, in like manner, provided with air inlet openings 30^a, controlled by valves 31, similar in all respects to the valve of the air chamber. Leading from the mixing chambers are pipes 32, which pipes may be connected to separate engines, valves 33 being preferably located in said pipes to control the passage of the motive fluid therethrough.

In charging the carbureter, the plug 25 is removed and the hydrocarbon or other suit-

able liquid is poured through the same into the channel 21. It will be seen that said channel will be completely filled and consequently, when it overflows, such overflow will take place on all sides, so that the fluid will be distributed equally over the body of absorbent material, thus obviating the danger of saturating one portion of the body prior to another portion. This is an important feature of the invention. The body of absorbent material having been thoroughly saturated, the supply opening 24 is again closed by the plug, and the valves 33 of the delivery pipes 32 are opened. As the engines are turned, it will be apparent that suction will take place through the pipes 32, thereby creating partial vacuums in the mixing chambers 10. As a result, the unbalanced outside air pressure will cause the valves 27 and 31 to open. The air will thus be passed through the absorbent body in the vaporizing chamber and the liquid therein vaporized, passing into the mixing chambers where it is properly commingled with the air that enters through the openings 30^a. Thence the charges pass to the engines.

By this construction, it will be apparent that motive fluid in proper condition to be exploded is delivered from the carbureters to the engines and is manufactured and supplied only as rapidly as the engines require, depending on the speed thereof. The richness of the mixture can be varied to suit the conditions of work by altering the resistance to the different inlet-controlling valves. Thus, by weakening the resistance to the valve 27 and strengthening the resistance against the valves 31, the vapor supplied to the engine can be as highly charged with hydrocarbon as desired. On the other hand, if the resistance against the opening of the valve 27 is made comparatively great and the spring action on the valves 31 is weakened, the reverse will take place. The structure, moreover, is exceedingly simple and can be manufactured at comparatively small cost. Furthermore, there is nothing that is liable to become inoperative or deranged, and the device, being compact, will occupy but little room, making it useful, particularly in cramped or confined places, such as automobiles. It will thus be seen that the carbureter disclosed is not only highly efficient, but economical in operation, and that a plurality or battery of engines can be run from the same without in any manner interfering. While two mixing chambers, and consequently two engines can be operated by the present device, it will be evident that a greater or less number of mixing chambers, and consequently of engines, can be connected to the vaporizing chamber and the structure still be entirely efficient.

From the foregoing it is thought that the construction, operation, and many advan-

tages of the herein described invention will be apparent to those skilled in the art, without further description, and it will be understood that various changes in the size, shape, proportion, and minor details of construction may be resorted to without departing from the spirit or sacrificing any of the advantages of the invention.

Having thus described our invention, what we claim as new and desire to secure by Letters Patent, is:

1. In a carbureter, the combination with a vaporizing chamber having spaced outer walls, of spaced perforate partitions extending across the chamber in spaced relation to the outer walls, forming an outer air compartment and an outer vapor compartment, means for admitting air to the air compartment, vapor-conducting means communicating with the vapor compartment, an absorbent body located between the perforate partitions, and a perforate tube located between the partitions and surrounded by the absorbent body, said tube communicating with one compartment, and being cut off from communication with the other.

2. In a carbureter, the combination with a vaporizing chamber having spaced outer walls, one of which is detachable and constitutes a closure for the chamber, of spaced perforate partitions extending across the chamber in spaced relation to the outer walls, forming an outer air compartment, and an outer vapor compartment, means for admitting air to the air compartment, vapor-conducting means communicating with the vapor compartment, an absorbent body located between the perforate partitions, and a perforate tube located between the partitions and surrounded by the absorbent body, said tube communicating with one compartment and having an imperforate terminal portion extending across the other compartment and engaged with the detachable outer wall.

3. In a carbureter, a vaporizing chamber having a top, a bottom, side walls, and perforated partitions located between the top and bottom and spaced from each other, forming an upper air compartment and a lower vapor compartment, a perforated tube extending between the partitions, a body of absorbent hydrocarbon-holding material arranged between the partitions and surrounding the tube, a valved air inlet for the air compartment, and vapor-conducting means having communication with the vapor compartment.

4. In a carbureter, a vaporizing chamber having an absorbent body, a partition located thereover and having a hydrocarbon-receiving channel, said partition being provided with openings alongside the channel, and means for admitting air to the vaporizing chamber.

5. In a carbureter, a vaporizing chamber

- having a transverse partition in its upper portion, an absorbent body located in the chamber below the partition, a perforated tube embedded in the body, said partition having a hydrocarbon-receiving channel in its upper side and extending about the tube, and perforations located on opposite sides of the channel, and means for admitting air to the vaporizing chamber.
- 5 6. In a carbureter, the combination with independent mixing chambers having separate air inlets, of a common vaporizing chamber communicating with both and also having an air inlet.
- 10 7. In a carbureter, the combination with independent mixing chambers having independent valved air inlets, of a common vaporizing chamber communicating with both and also having an air inlet, and means for 15 respectively connecting the mixing chambers to separate engines.
8. In a carbureter, the combination with a 20 casing, of upright interior walls dividing the same into outer mixing chambers and an intermediate vaporizing chamber, said vaporizing chamber communicating with both the mixing chambers, a body of absorbent hydrocarbon-holding material located in the vaporizing chamber, a valved air inlet to the 25 vaporizing chamber on the side of the absorbent body that is opposite to the com-
- munication of the vaporizing with the mixing chambers, and valved air inlets communicating with the mixing chambers.
9. In a carbureter, the combination with a 30 closed casing, of upright interior walls located therein, and defining outer mixing chambers and an intermediate vaporizing chamber, said walls having perforations in their lower portions, constituting means of communication between the chamber's, spaced substantially horizontal perforated partitions located in the vaporizing chamber and forming an upper air compartment and a lower vapor compartment, the latter being in 35 communication with the mixing chambers, a perforated tube located between the partitions and communicating at its lower end with the vapor chamber, a body of absorbent material surrounding the tube and located 40 between the partitions, a valved air inlet for the air compartment, and valved air inlets for the mixing chambers.
- 45 In testimony, that we claim the foregoing as our own, we have hereto affixed our signature in the presence of two witnesses.
